UNITED STATES PATENT OFFICE.

ALBERT GOTTSCHALK, OF NEW YORK, N. Y., ASSIGNOR TO NATIONAL PNEUMATIC COMPANY, OF NEW YORK, N. Y., A CORPORATION OF WEST VIRGINIA.

EMERGENCY DOOR-CONTROL APPARATUS.

Application filed December 16, 1922. Serial No. 607,450.

To all whom it may concern:

Be it known that I, ALBERT GOTTSCHALK, a citizen of the United States, residing at New York, county of Bronx, State of New York, have made a certain new and useful Invention in Emergency Door-Control Apparatus, of which the following is a specification.

This invention relates to apparatus which may be utilized in the case of an emergency for controlling the doors on street cars, or the like.

The object of the invention is to provide an emergency control, and more particularly, power control of the doors on street cars, or the like, which is simple in structure, efficient in operation, economical of manufacture, and requires but few additional parts.

20 A further object of the invention is to provide an emergency control for doors on street cars, and the like, which will permit power control of the doors to open the same in the event the standard equipment becomes inoperative, or the power supply exhausted.

Further objects of the invention will appear more fully hereinafter.

The invention consists substantially in the construction, combination, location, and relative arrangement of parts, all as will be more fully hereinafter set forth, as shown in the accompanying drawing, and finally pointed out in the appended claims.

35 Referring to the drawing:

The single figure shows diagrammatically the layout on a car of the emergency door control apparatus embodying my invention.

In the street car art the standard equipment now employed consists of a pneumatic motor for controlling the opening and closing movements of the door, which motor may be controlled electrically, pneumatically, or electro-pneumatically. The prime motive power, however, is fluid pressure, and consequently in the event of an emergency, where the fluid pressure has been allowed to escape, or if the electric, pneumatic, or electro-pneumatic control of the door motor fails, it has heretofore been extremely difficult to manually, or otherwise, open the doors, with the result that the passengers have become entrapped in the car, with ensuing panic and injury to the various passengers resulting therefrom. In electric

systems, for example, in the subways in New York, where, as is apt to occur, insulation is set on fire, and the strong fumes therefrom, which are not only obnoxious, but in some instances, dangerous, are confined to the tubes beneath the surface, the inability to open car doors in an emergency might readily result in loss of life.

In accordance with my invention, I have provided an emergency control of the door apparatus, which, at all times, will permit the ready operation of the door motors entirely independent of the normal operation thereof by the guard or conductor. Referring to the drawing wherein I have diagrammatically illustrated a system embodying the principles of my invention, reference numeral 1 designates a plan layout of a car, showing the standard equipment employed in a car as follows: The pneumatic door motors 2 are arranged for end and center door control, three motors being shown on each side of the car. The air compressor, which supplies fluid pressure to the motors, is diagrammatically illustrated at 3, and is connected by pipe 4, to what is called the main reservoir 5, where the compressed air supplied from the compressor 3 is stored. A pipe line 6 and 7, communicating with the main reservoir 5, leads to the respective ends 85 of the car to the motorman or guard control 8, from which point the motorman or guard can control selectively or simultaneously the operation of the respective motors either electrically, pneumatically, or electro-pneumatically, and in any manner well known and at present employed in the art. The foregoing standard part of the equipment forms no part of my present invention, and therefore has been shown in the most simplified manner, and entails the elimination from the illustration of the many refinements and additional instrumentalities employed in connection therewith with which the art is familiar. In accordance with my invention, 100 however, I provide the auxiliary pipe line 9 leading from the main reservoir 5, which pipe line 9 has a check or one way valve 10, which permits fluid pressure from the main reservoir 5 to flow therefrom, but prevents 105 any fluid pressure from flowing thereto. The pipe line 9 connects with what I will term the emergency reservoir 11. Fluid pressure from the main reservoir 5 fills the emergency reservoir 11, which, if desired, 110

may be of smaller size than reservoir 5. The emergency reservoir 11 is connected by pipe line 12 to a valve 13, which is preferably mechanically operated, and which is connected by line 14 to all of the door motors. From the foregoing it will readily be seen that in the event the normal door control system becomes defective or inoperative the operation of one emergency valve will simultaneously open all of the doors on the car, or train of cars, as the case may be, and the fact that the emergency reservoir is at all times filled enables this emergency operation irrespective of any injury to the normal door control system.

Many modifications and changes in details will readily occur to those skilled in the art without departing from the spirit and scope of my invention as defined in the 20 claims, but having now set forth the objects and nature of my invention, and having shown and described a system embodying the features thereof, what I claim as new and useful and of my own invention 25 and desire to secure by Letters Patent is:

1. An emergency door operating mechanism comprising, in combination with a door and a motor therefor and a main pressure reservoir for supplying fluid pressure for the normal operation of said motor, an auxiliary reservoir, means for maintaining said auxiliary reservoir filled, and means for utilizing pressure from said auxiliary reservoir for actuating said door.

2. An emergency door operating mechanism comprising, in combination with a plurality of doors and door motors therefor and a main pressure reservoir, an auxiliary reservoir, means for maintaining said auxiliary reservoir filled, and means for utilizing pressure from said auxiliary reservoir for actuating all of said doors simultaneously.

3. An emergency door operating mechanism comprising, in combination with a door and motor therefor and a main pressure reservoir for supplying fluid pressure for the normal operation of said motor, an auxiliary reservoir, means for maintaining said auxiliary reservoir filled from said main reservoir, and means for utilizing pressure from said auxiliary reservoir to actuate said door.

4. An emergency door operating mechanism comprising, in combination with a plurality of doors and door motors and a main pressure reservoir, an auxiliary reservoir, means for maintaining said auxiliary

reservoir filled from said main reservoir, and means for utilizing pressure from said auxiliary reservoir to actuate all of said doors simultaneously.

5. An emergency door operating mechanism comprising, in combination with a door and motor therefor and a main pressure reservoir for supplying fluid pressure for the normal operation of said motor, an auxiliary reservoir, means for maintaining said auxiliary reservoir filled, and means for supplying pressure from said auxiliary reservoir to said door motor independently of the normal control of said motor.

6. An emergency door operating mechanism comprising, in combination with a plurality of door motors and a main pressure reservoir, an auxiliary reservoir, means for maintaining said auxiliary reservoir filled, and means for supplying pressure from said auxiliary reservoir to all of said door motors simultaneously independently of the normal control of said motors.

7. An emergency door operating mechanism comprising, in combination with a door motor and a main pressure reservoir for supplying fluid pressure for the normal operation of said motor, an auxiliary reservoir, means for maintaining said auxiliary reservoir filled from said main reservoir, and means for supplying pressure from said auxiliary reservoir to said door motor independently of the normal control of said motor.

8. An emergency door operating mechanism comprising, in combination with a plurality of door motors and a main pressure reservoir, an auxiliary reservoir, means for maintaining said auxiliary reservoir filled from said main reservoir, and means for supplying pressure from said auxiliary reservoir to all of said door motors simultaneously independently of the normal control of said motors.

9. An emergency door control mechanism comprising a door and an auxiliary reservoir, a main reservoir for supplying fluid pressure to said auxiliary reservoir, means for preventing the return of said fluid pressure supply to said main reservoir, and means for actuating the door by the fluid pressure contained in said auxiliary reservoir.

In testimony whereof I have hereunto set my hand on this 11th day of December A. D., 1922.

ALBERT GOTTSCHALK.
